US00D847868S

(12) **United States Design Patent** (10) **Patent No.:** **US D847,868 S**
Wilhelmi et al. (45) **Date of Patent:** **** May 7, 2019**

(54) **SEED DISK WITH INTEGRATED HUB**(71) Applicant: **Kinze Manufacturing, Inc.**,
Williamsburg, IA (US)(72) Inventors: **Matthew Wilhelmi**, Williamsburg, IA
(US); **Collin Vondracek**, Williamsburg,
IA (US); **Philip Willis**, Williamsburg,
IA (US)(73) Assignee: **Kinze Manufacturing, Inc.**,
Williamsburg, IA (US)(**) Term: **15 Years**(21) Appl. No.: **29/612,142**(22) Filed: **Jul. 28, 2017**(51) LOC (11) Cl. **15-03**

(52) U.S. Cl.

Primary Examiner — Mark A Goodwin

(74) Attorney, Agent, or Firm — McKee, Voorhees &
Sease, PLC(57) **CLAIM**We claim the ornamental design for a seed disk with
integrated hub, substantially as shown and described.

DESCRIPTION

FIG. 1 is a front isometric view of the seed disk with
integrated hub;FIG. 2 is rear isometric view of the seed disk with integrated
hub;FIG. 3 is a front plan view of the seed disk with integrated
hub;FIG. 4 is a rear plan view of the seed disk with integrated
hub; and,FIG. 5 is a side elevation view of the seed disk with
integrated hub.A description of the appearance of the article is as follows:
The broken lines represent portions of the article, and form
no part of the claimed design.**1 Claim, 5 Drawing Sheets**| (56)	References Cited
